J. H. Walker.

United States Patent Office.

J. H. WALKER, OF WORCESTER, MASSACHUSETTS.

Letters Patent No. 71,929, dated December 10, 1867.

IMPROVED MACHINE FOR ROLLING LEATHER.

The Schedule referred to in these Letters Patent and making part of the same.

TO ALL WHOM IT MAY CONCERN:

Be it known that I, J. H. WALKER, of the city and county of Worcester, and Commonwealth of Massachusetts, have invented certain new and useful Improvements in Machines for Rolling Sides of Leather; and I do hereby declare that the following is a full, clear, and exact description of the same, reference being had to the accompanying drawings, forming a part of this specification, in which—

Figure 1 represents a front view of my improved machine.

Figure 2 represents a section on line A B, fig. 1.

To enable those skilled in the art to which my invention belongs to make and use the same, I will proceed to describe it more in detail.

In the drawings, the parts marked A A are the upright frame-pieces, made fast at the bottom to base-pieces B B. The upright pieces A A are united at the top by pieces C C, and the upright pieces at each end are also connected by cross-pieces D, to give the frame strength. Truss-rods E E pass from the end pieces at each end over the bridge-piece F, which rests upon the tops of the pieces C, to the under side of which is fastened the horizontal tongued way G, upon which the slide-piece H works. From the bottom of the slide-piece H project the arms α α , between which the roll b is journaled. Pitman I connects the slide H with the wheel J, by means of which a reciprocating motion is imparted to the slide H and roll b . K is the table, upon which the side of leather to be rolled is placed. Table K is supported at each end by the upright pieces A A, and is slotted or cut out in the centre to admit the face L of the hinged table M to pass up, as shown in red and dotted lines in the drawings. The outer end of table M is hinged at c, between the end-pieces of the frame, while the inner end plays up and down in a slot in the stand N, which rests upon and is fastened to the base O. One end, d, of a toggle-joint or lever rests in a recess in the base O, while the upper end, e, of the same lever works in a recess in the under side of the hinged table M, the centre of said lever being connected to the crank P by the hinged rod Q. Crank P is connected to a shaft or journal, which is supported and turns in the upper end of the stand S, upon the projecting piece T. Foot-lever U is fastened near its rear end to the end of the shaft or journal to which the crank P is fastened. A weight, V, is arranged upon the rear end, f, of the foot-lever U, all as fully shown in the drawings.

The operation is as follows: Power being communicated to wheel J, in any convenient manner, a rapid reciprocating motion is imparted to slide H and roll b . The operator now places a side of leather upon table K, under the roll b , and then presses upon the foot-lever U, thereby causing the parts to move into the positions shown in red lines, the face L of the hinged table M passing a part of the side of leather up to the action of roll b .

It will be seen that the operator can cause the leather to be pressed between the face L of table M and roll b with any desired degree of pressure, and that he can readily move the side of leather to roll any part of the side. The machine is compact, compared with the old style, in which the roll b is inserted in the end of a long pendulum or lever.

Having described my improved machine for rolling sides of leather, what I claim therein as new, and of my invention, and desire to secure by Letters Patent, is—

1. The combination of the horizontal way G, slide H, and roll b , with tables K and M, and treadle-operating device, substantially as and for the purposes set forth.
2. The combination, with the pieces C C, of the truss-rods E E, bridge F, way G, and slide H, substantially as and for the purposes set forth.

J. H. WALKER.
